ALEXANDER K. RIDER, OF ELIZABETH CITY, NEW JERSEY.

Letters Patent No. 89,344, dated April 27, 1869.

IMPROVEMENT IN PUMP-VALVES.

The Schedule referred to in these Letters Patent and making part of the same.

To all whom it may concern:

Be it known that I, ALEXANDER K. RIDER, of Elizabeth City, and county of Union, in the State of New Jersey, have invented certain new and useful Improvements in Pumps; and I do hereby declare that the following is a full and exact description thereof.

My invention relates to the construction of the valves, and of the parts and passages adjacent thereto.

I will first describe what I consider the best means of carrying out my invention, and will afterwards designate the points which I believe to be new.

I employ a tube, preferably vulcanized rubber in whole or in part, to serve as each valve, there being four independent valves, and I provide a bonnet at each end of each valve-chamber, connected together by a bolt, which passes through the valve-chamber in the space within the interior of the tube which serves as the valve.

The valve has sufficient play to perform properly, while it need not touch the bolt at all; that is to say, the cavity within the valve is so much greater than the bolt, that the valve may close tightly, and again open to its widest extent, by moving bodily in one direction or the other, while the bolt stands unaffected in the space in its interior.

The accompanying drawings form a part of this specification.

Figure 1 is a longitudinal section, and

Figure 2, a cross-section on line S S, through the entire pump.

Figure 3 is a cross-section through the valve, and its seat and cage on a larger scale.

Figure 4 is a longitudinal section through the same, on the inclined line T T, in fig. 3.

The remaining figures show different modifications in the construction or material of the valve.

Figure 5, a cross-section, all rubber;

Figure 6, a cross-section, all brass;

Figure 7, a cross-section, part brass and part rubber;

Figure 8, a cross-section, part rubber and part linen; and

Figure 9, a cross-section, all iron.

Similar letters of reference indicate corresponding parts in all the figures.

A is the cylindrical chamber, which forms the body of the pump proper, and B is a piston of any approved construction, reciprocated therein by any approved means. It may be operated by steam or other power, may stand in the perpendicular, horizontal, or variously inclined position, may be made of cast-iron, brass, or other suitable material, may be lined, enamelled, or otherwise prepared, and the piston may be constructed and packed in any approved manner. In short, the pump, in all the points other than those to which my invention directly relates, may be of any approved kind.

Ports or passages, which admit the water into the

barrel A of the pump, and permit its discharge, are indicated by I I I.

A cylindrical hole, larger than the valve, is bored, or otherwise produced, so as to form a chamber in the port, extending directly through the casting which forms the body of the pump. Into this is fitted a bushing, M, peculiarly constructed, as will be described further on.

The several valves are indicated by N. Each is mounted in a hole in its bushing M, so as to have liberty to play, as above intimated.

The bonnets O' O² cover the end of each valve-chamber and bushing, and are connected together by the bolt D.

The four valves, and their respective bushings, may be exactly alike. A minute description of one will serve for the whole, the only difference necessary being the change of position or inclination.

The valve N may be formed entirely of vulcanized rubber, or it may serve a tolerable purpose if formed entirely of brass, iron, or various other material, but necessarily in the form of a cylinder. The preferable construction, however, is a tube of India rubber, drawn tightly over a tube of brass, or other suitable metal. This construction is indicated in fig. 7, the outer elastic material being indicated by N¹, and the inner unyielding material being indicated by N².

The bushing M is hollowed out by coring, or by suitable tools, or partly by each of these processes, so as to form a seat, J, which may be grated or cross-barred, as indicated, to afford a better bearing for the valve when it shuts upon its seat.

The width of the seat corresponds to the width of the port I, and the metal of the bushing M is solid on each side of the seat. In other words, when by the force of the water the valve is pressed down upon its seat, it covers tightly the entire communication through the passage, or port I, and forbids the access of water from either side. In other words, it is a tight valve when shut.

When the force of the water lifts the valve, it is allowed, by the form of the chamber m, within the bushing M, to rise from its seat, but the rise is limited, as represented; that is to say, when it has risen to a sufficient height to allow the water to flow freely around it through passages, now to be described, its further rise is arrested, and it remains in that position, allowing the water to flow past it on each side. The passages for the flow of the water in this manner are indicated by m'. These passages are very capacious, and they are divided simply by slight webs M'. These webs may be connected together around the whole exterior of the bushing, excepting immediately against the ports I I; that is to say, the water enters freely on one side of the bushing, and flows out freely on the other side.

The remaining surface of the bushing may be either grated or ribbed, or it may be a continuous shell. I

prefer the latter construction, as represented in the drawings.

It will now be seen that, in the working of the pump, my several induction and eduction-valves move away from their seats, and again return to them, by the action of the water. In other words, they are self-acting valves, like ordinary pump-valves, and that they close upon their seats with all the tightness due to a correct adaptation of the forms of the parts to each other, and also with the capacity to adapt themselves to inequalities and imperfections due to the India-rubber material on the valve, and that they allow very long ports measured in the transverse direction across the cylinder, and that they allow very capacious openings, and a very free discharge of the water around them.

The valve is caged by the bushing very effectually, and in case any derangement or clogging should possibly occur, or any repairs ever become necessary, one or both the bonnets may be removed by simply taking off a nut from the bolt D, and the valve may be immediately drawn out and examined. The bushings M may be also removed for examination or repairs, if desired.

My invention, as above described, may be applied on pumps, for pumping hot or cold water, air, gases, or any fluid which will not affect the materials.

In case oils, acids, or the like are pumped, which will affect rubber, I make the valve entirely of metal, or of metal covered with leather, felt, or other suitable soft material which will remain unaffected.

In constructing my pump for pumping air, I esteem it important to place the valve and its bushing as near the main chamber A as is practicable.

The construction of my valve in two concentric tubes,

the exterior of rubber, and the interior of brass, or the like, renders it practicable to secure the requisite stiffness and strength in the valve, with great capacity for adapting itself to irregularities in the seat, while the whole of the moving parts may be extremely light, and ready to move with the least amount of resistance from inertia or other cause.

I can dispense with separate bushing by casting the valve-chambers in one piece with the pump, giving such chambers the same internal form as the bushings described.

Having now fully described my invention,

What I claim as new, and desire to secure by Letters Patent, is as follows:

1. The cylindrical valve N, seat J, and cross-bars, or grids M', constructed and arranged as represented, relatively to each other, and to the ports I I of a pump, for the purposes herein set forth.

2. The freely-rolling, or shifting valve N, having an exterior of soft rubber, and an interior of metal, when made in the form of a hollow cylinder, and mounted to work upon a cylindrical seat, in the manner and for the purposes herein set forth.

3. The combination of the removable bushing M, formed with a seat, J, and webs M', as represented, the bonnets C' O', the through-bolt D, and the tubular valve N, constructed, combined, and arranged as represented, for the purposes herein set forth.

In testimony whereof, I have hereunto set my name in the presence of two subscribing witnesses.

A. K. RIDER.
